UNITED STATES PATENT OFFICE.

JOSEF MRÓZ, OF VIENNA, AUSTRIA.

APPARATUS FOR TAKING THE COLOR-COMPONENT NEGATIVES FOR MULTICOLOR PHOTOGRAPHY.

Application filed February 25, 1922. Serial No. 539,163.

To all whom it may concern:

Be it known that I, JOSEF MRÓZ, mechanical engineer, a citizen of the Republic of Poland, residing at Vienna, in Lower Austria and Republic of Austria, have invented certain new and useful Improvements in an Apparatus for Taking the Color-Component Negatives for Multicolor Photography, of which the following is a specification.

10 The periodically successive taking of negatives for multi-color cinematographic films is known. With this method, the color-screens or light-filters corresponding to the color-component negatives are automatically 15 and periodically brought to the place of exposure in accordance with the rate of the intermittent movement or advance of the film. The film as well as the color-screens are generally driven by means of a crank 20 operated by hand.

According to my invention I intend to use this known principle for ordinary multicolor photography, i. e. not for cinematography. However it is not possible to use 25 the known driving device for the film without essential changes in this device, because with ordinary photography, only three component photographs have to be taken in case of three-color photography, and therefore 30 by it is impossible to regulate the rotation of the hand-crank in such a manner as to stop the film exactly after three sections of movement if with instantaneous exposures a rapid rotation is required.

35 According to my invention the driving mechanism is operated by a mechanism actuated by weight or by spring and liable to be freed for operation, the tension of the mechanism produced by the weight or the 40 spring being variable in order to vary the speed of running of the film and consequently the duration of exposure of the instantaneous photograph, and the running movement of the driving mechanism being 45 limited by stops. Therefore it is sufficient to free the click of the driving mechanism kept under tension, in order to have it automatically run to such a degree so that only exactly the desired number of component 50 views may be produced on the film. For time-exposures the driving mechanism may be combined with a hand crank for actuating. However such time-photographs may also be automatically taken by means of the 55 driving mechanism under tension.

In the annexed drawing a mode of execution of the apparatus according to my invention is represented, Fig. 1, being a front elevation and Fig. 2 a side elevation.

The axis 1 of the drying drum 2 of the 60 film carries the known Maltese cross 3 in which engages the pin 4 of the disc 5 mounted on the driving shaft 6. This shaft 6 carries a loosely mounted toothed wheel 7 engaging with a toothed sector 8 mounted on 65 an axis 9; a spring 10 connected to the sector 8 tends to rotate it upwards. The upward rotation of the toothed sector is limited by a pin 11 engaging in a concentrically arranged slot 12 in the toothed sector. The 70 end of the spring 10 is connected to a disc 13 by the rotation of which the initial tension of the spring may be varied and adjusted. The toothed sector 8 may be rotated downwards by means of a button 14 fixed 75 to the axis 9 of the sector, which button is outside the casing of the apparatus and thereby the tension of the spring 10 is increased. A downward rotation of the sector 9 is limited by the snapping of the 80 pin 15 mounted on a flat spring 16 into a recess 17 of the toothed sector 8, thereby fixing it against the action of the spring 10. The flat spring 16 is provided with a pin 18 85 projecting to the outside of the casing and having there a knob 19. By pressing this knob 19 inwardly the flat spring 16 is moved so as to withdraw the pin 15 from the recess 17 of the toothed sector 8, so that this sector is released and is rotated upwards by 90 the spring 10, thereby driving by means of the toothed wheel 7 the disc 5 and pin 4, the Maltese cross 3 and with it the driving drum 2, this being rotated intermittently in consequence of the Maltese cross Mechanism. 95

The degree of rotation of the toothed sector 8 is limited by the engagement of the pin 11 in the slot 12 in such a manner that the film is only moved for the required three 100 color component sections in case of a three-color photograph. The toothed wheel 7 loosely mounted on the shaft 6 is connected with one part 20 of a coupling device, the second part 21 of which is fixed on the 105 shaft 6. The coupling device is constructed in such a manner that coupling is effected only in one direction of rotation whereas in the other direction no coupling effect is produced. The first part 20 of the cou- 110

pling device is provided with a grooved disc 22; part 20, toothed wheel 7 and grooved disc 22 are united to form a single piece which is pressed against the second part 21 of the coupling by means of a spiral spring 23. An oblique member 24 mounted on a bolt engages the grooved disc 22; this bolt may be rotated by means of the button 25 in such a manner that this member 24 thereby withdraws the coupling part 20 from the coupling part 21 against the action of the spring 23. The teeth of the coupling are so directed that when the coupling is engaged, the movement of the toothed sector 8 in one direction is transmitted to the shaft 6 whereas with the back rotation of the toothed sector 8 by means of the button 14, the shaft 6 is not moved.

Outside the casing the shaft carries a hand-crank 26 adapted to directly drive the shaft 6 if time-exposures have to be made. In order to avoid that the toothed sector makes the rotation, which in the case of actuating the driving by means of a hand-crank is superfluous, the coupling device 20, 21 may be disengaged by a short rotation of the button 25 so that the toothed wheel 7 is not obliged to rotate with the axis 6, when this latter is driven by the crank 26. In order to prevent an opposite rotation of the crank the shaft 6 carries a ratchet-wheel 27, in the teeth of which a pawl engages.

The shaft 6 is further provided with a bevel gear 28, which by means of the bevel gear 29 drives the shaft 30, which by means of a worm gear 31, 32 rotates the disc 33 having three diaphragm openings 33*; simultaneously they contain also the color-screens. These three (red, green, blue) screens advance to the place of exposure according to the intermittent progression or advance of the film.

The combination of the single features as described constitute a simple, photographic apparatus for photochromatic or multi-color photography, for the actuating of which for instantaneous photographs, it is sufficient to predetermine the duration of the instantaneous exposure by means of the button displacing the disc 13 and varying thereby the initial tension of the spring 10,—to rotate the knob 14 for effecting a tension of the automatic driving mechanism—and to press the knob 19 inwardly for disengaging the click of the driving mechanism, whereupon the driving mechanism automatically runs down and in consequence of its limitation imparts to the film only three successive movements in advance. Simultaneously the three color-screens are automatically and in succession brought before the place of exposure. In case of time-exposures having to be made by means of

the crank, the coupling device 20, 21 is first 65 disengaged by rotating the button 25.

In accordance with the patent statutes, I have shown and described the preferred form of this invention: but I desire it to be distinctly understood that I fully realize 70 that changes may be made in the structure herein disclosed and that I intend to include within the scope of the claims that follow hereinafter all modifications of the preferred form of this invention that do not 75 depart substantially from the spirit thereof.

What I claim is:

1. In an apparatus for taking the color-component negatives for multi-color photography the combination of a mechanism for intermittently moving a film on the back of an objective, a toothed sector engaging with a toothed wheel driving the said mechanism, a spring connected to the said toothed sector, tending to rotate it in such a direction 80 so as to drive the film forwards, a click engaging with a stop of the toothed sector in its position under tension, means for disengaging this click, a device for stopping the toothed sector after its automatic movement which has caused the film driving mechanism to bring the required number of film sections in coincidence with the objective, a movable carrier of light-filters and a mechanism for automatically bringing these 85 filters successively in coincidence with the objective in the same measure of time as the film sections come in coincidence with the objective. 90

2. In an apparatus for taking the color-component negatives for multi-color photography the combination of a mechanism for intermittently moving a film on the back of an objective, a toothed sector engaging with a toothed wheel driving the said mechanism, a spring connected to the said toothed sector, tending to rotate it in such a direction so as to drive the film forwards, a click engaging with a stop of the toothed sector in its position under tension, means for disengaging this click, a device for stopping the toothed sector after its automatic movement which has caused the film driving mechanism to bring the required number of film sections in coincidence with the objective, a carrier 100 of light-filters, and a mechanism for moving it in such a manner that the light-filters come successively in coincidence with the objective in the same measure of time as the film sections come in coincidence with the objective, the moving mechanism for these filters being driven by the mechanism driven by the toothed sector. 105

3. In an apparatus for taking the color-component negatives for multi-color photography the combination of a mechanism for intermittently moving a film on the back of an objective, a toothed sector engaging with 110

a toothed wheel driving the said mechanism, a spring connected to the said toothed sector, tending to rotate it in such a direction so as to drive the film forward, a click engaging with a stop of the toothed sector in its position under tension, means for disengaging this click, a device for stopping the toothed sector after its automatic movement which has caused the film driving mechanism to bring the required number of film sections in coincidence with the objective, a rotatable disc carrying a number of light-filters and a mechanism for driving the said disc in such a manner that the light-filters come successively in coincidence with the objective in the same measure of time as the film sections come in coincidence with the objective, the driving mechanism of the said disc being driven by the mechanism driven by the toothed sector.

5 a film on the back of an objective, with a 25 device under tension for driving this mechanism, a device for automatically stopping the film after the exposure of the required number of color-component sections of the film, a movable carrier of light-filters, a 30 mechanism for automatically bringing these filters successively in coincidence with the objective in the same measure of time as the film sections come in coincidence with the objective, the device for actuating the film 35 driving mechanism for the film being provided with a coupling device for enabling a disengagement of the connection between this actuating device and the film driving mechanism, this mechanism being adapted 40 to be driven by hand for exposures of longer duration.

In testimony whereof I affix my signature.

JOSEF MRÓZ.
